Primary Examiner — Joseph Kukella*Assistant Examiner* — Darryl J Dardenne(74) *Attorney, Agent, or Firm* — Leason Ellis LLP(57) **CLAIM**

The ornamental design for a pitcher, as shown and described.

DESCRIPTION

FIG. 1 is a perspective view of a pitcher according to my new design;

FIG. 2 is a right-side elevation view thereof, the left side being a mirror image;

FIG. 3 is a front view thereof;

FIG. 4 is a rear view thereof;

FIG. 5 is a top plan view thereof; and,

FIG. 6 is a bottom plan view thereof.

The grayscale shading depicts a contrast which is part of the claimed design without claiming any particular color.

Conventional shading is illustrated for purposes of highlighting the line drawings, but forms no part of the claimed design.
